DESIGN FOR A HANDCAR

Samuel A. Snell, Toledo, Ohio, assignor to The American-National Company, Toledo, Ohio, a corporation of Ohio

Application March 14, 1938, Serial No. 75,810

Term of patent 7 years

To all whom it may concern:

Be it known that I, Samuel A. Snell, a subject of the King of Great Britain and Northern Ireland, residing at Toledo, in the county of Lucas and State of Ohio, have invented a new, original, and ornamental Design for a Handcar, of which the following is a specification, reference being had therein to the accompanying drawing, forming a part thereof, wherein:

The figure is a perspective view of a handcar embodying my new design.

I claim:

The ornamental design for a handcar substantially as shown.

SAMUEL A. SNELL.
